UNITED STATES PATENT OFFICE

112,214

DESIGN FOR A DECORATIVE PLATE FOR AN AUTOMOBILE RADIATOR GRILLE OR TRUNK

Carl Reynolds, Jr., Detroit, Mich., assignor to General Motors Corporation, Detroit, Mich., a corporation of Delaware

Application September 25, 1937, Serial No. 71,794

Term of patent 3½ years

To all whom it may concern:

Be it known that I, Carl Reynolds, Jr., a citizen of the United States and a resident of Detroit, county of Wayne, and State of Michigan, have invented a new, original, and ornamental Design for Decorative Plate for an Automobile Radiator Grille or Trunk, of which the following is a specification, reference being made to the accompanying drawing, forming a part thereof.

Figure 1 is a plan view of a decorative plate for a radiator grille or trunk showing the novel design.

Figure 2 is a front elevation thereof, and Figure 3 is a side elevational view thereof.

I claim:

The ornamental design for a decorative plate for an automobile radiator grille or trunk, as shown.
